pany, Dallas, Tex., a corporation of Delaware,
and one-half to Eastman Oil Well Survey Cor-
poration, Long Beach, Calif., a corporation of
California

Application January 30, 1942, Serial No. 428,875

10 Claims. (Cl. 33—27)

This invention relates to new and useful im-
provements in methods of and means for marking
record elements.

In the well survey art, the use of record or
index elements have come into general use, such
elements usually taking the form of a circular
disk. This disk is arranged to be mounted within
a suitable holder or carrier in a well survey in-
strument and when in position within said instru-
ment, is associated with a plumb bob or pendulum
which is located thereabove and which, upon an
inclination of the instrument from the vertical,
swings relative to the center of the disk or ele-
ment. A marking means, either mechanical or
photographic, is adapted to mark the record ele-
ment in accordance with the position of the
plumb bob, whereby the mark so formed is indi-
cative of the inclination of the instrument. To
those familiar in this art, it will be apparent
that when the instrument is inclined, due to its
being lowered in an inclined well bore, the plumb
bob remains vertical, with the result that the
lower end of the plumb bob moves off-center of
the record disk therebelow. By marking the
position of the plumb bob relative to the record
disk and then determining the number of de-
grees that the mark is from the center of said
disk, the inclination of the instrument, in degrees,
may be ascertained.

The present invention is not concerned with
the construction of the well survey instrument,
or of the plumb bob or of the particular means
for marking the position of the plumb bob,
whether such means be photographic or me-
chanical. However, it has been found that in
order to accurately determine the exact position
of the mark, which indicates the plumb bob pos-
ition, it is desirable, and almost essential, that
the record element or disk be imprinted or pro-
vided with concentric reference lines which are
representative of degrees. These lines have ordi-
narily been printed on the disk at the time, or
subsequent to, the cutting out or formation of
said disk. Obviously, because of the extreme
accuracy required, it has been difficult to accu-
rately position said lines so that they are exactly
concentric to the center of said disk. The slight-
est movement of the disk during printing results
in inaccuracy of positioning of the lines and sub-
sequently, in an inaccurate reading of the record
obtained.

One object of the invention is to provide an
improved method for forming the concentric
reference lines on the record element or disk

after the disk has been formed, whereby extreme
accuracy in positioning said lines is assured.

An important object of the invention is to
provide an improved method of forming the con-
centric reference lines on a record disk which
consists in first mounting the disk in a carrier
or support, and then bringing said disk into con-
tact with a marking block, and then rotating
said block while preventing lateral displacement
of the block relative to the disk, to imprint or
form the reference lines on said disk.

A particular object of the invention is to pro-
vide an improved apparatus for forming the
concentric reference lines on a record disk in-
cluding a circular marking block having an outer
diameter substantially equal to the disk so that
said block will fit within the carrier or support
which carries said disk, whereby said carrier or
support acts as a guide to prevent lateral dis-
placement of the block relative to the disk during
the marking operation and also whereby accu-
rate positioning of the lines, exactly concentric
to the center of said disk, is assured.

A further object of the invention is to provide
an improved apparatus of the character described
wherein the marking block is provided with con-
centric annular marking ridges or projections
constructed of a metal capable of marking the
material of which the record element is con-
structed, the provision of said ridges assuring
that all disks are marked or lined in an identical
manner.

Still another object of the invention is to pro-
vide an apparatus, of the character described,
wherein the material, of which the record ele-
ment is constructed, may be coated on one sur-
face with a suitable substance which will facili-
tate marking of said surface by a relatively soft
metal, such as brass, or the like.

The construction designed to carry out the
invention will be hereinafter described together
with other features of the invention.

The invention will be more readily understood
from a reading of the following specification and
by reference to the accompanying drawing, as
an example of the invention is shown, and
wherein:

Figure 1 is an elevation of the marking device,
constructed in accordance with the invention.

Figure 2 is a transverse, vertical sectional view,
taken on the line 2—2 of Figure 1.

Figure 3 is a bottom view of the marking de-
vice, illustrating the annular concentric marking
ridges or projections,

Figure 4 is an isometric view of the upper por-

tion of the support for the record element and showing said element removed therefrom.

Figure 5 is a transverse, vertical sectional view of the support having the record element mounted therein, and of the marking device engaged with said disk to perform the marking operation.

Figure 6 is a view, similar to Figure 4, with the record element within its support after the marking operation has been completed to form the concentric reference lines on said element, and

Figure 7 is a plan view of the record element having the reference lines thereon.

In the drawing, the numeral 10 designates a solid head or body which is formed with an integral, depending skirt or collar 11. The outer periphery of the head or body may be knurled as shown at 12 to facilitate manual gripping thereof. The bore 13 of the annular skirt 11 is adapted to receive a marking block 14 which is provided with an external annular flange 15 at its upper end. The upper surface of the block 14 engages the bottom 16 of the head or body 10 and is held in position within the bore of the skirt by an upstanding stud or pin 17 which is preferably formed integral with the block and which is threaded into an axial bore 18 formed in the head or body.

The bottom or lower surface of the marking block 14 is formed with a plurality of ridges or projections 19 which are preferably integral with the block. As is clearly shown in Fig. 2, each ridge is substantially triangular in cross-section with the apex of the triangle being at the lower end and with this arrangement, the edges of the ridges or projections are sharpened to substantially a knife-edge. A single conical projection 20 is disposed at the center of the block, as is clearly indicated in Fig. 3, but if desired, this projection may be omitted. The annular projections or ridges 19 are arranged in concentric relation and five of such ridges or projections are shown, the ridges being indicated by the numerals 19a, 19b, 19c, 19d and 19e in Fig. 3. Each projection or ridge is representative of a predetermined number of degrees from the center projection 20 of the block. For the purposes of this description, it will be assumed that the projections are each representative of one degree, moving outwardly from the center of the block. Thus, the projection 19a indicates one degree of inclination from the center projection 20, the projection 19b indicates two degrees and so on to the outer peripheral edge of the block.

The marking device illustrated in Figures 1 to 3 is adapted to form concentric reference lines on a record element or disk 21. This element may be formed of paper, or other suitable material and is arranged to be mounted within a carrier 22 of a well survey instrument (not shown). The carrier includes a cylindrical body 23 which is formed with an annular collar 24 preferably made integral with its upper end. The bore 25 of the collar is of the same diameter as the diameter of the record element or disk 21, whereby the disk has a snug fit within the collar. The collar is of a sufficient height that when the disk is in position therein, as illustrated in Figure 5, the upper surface of the disk is in a plane well below the upper edge of the collar 24. A V-shaped notch 26 may be formed at one side of the collar 24, said notch extending downwardly from the upper edge thereof and this notch permits a pointed instrument to be inserted beneath the disk 21 to facilitate removal of said disk from the carrier or support 22.

The upper surface 27 of the carrier or support, which surface is engaged by the disk 21 when the same is in position within the collar 24, is shown as being arcuate or slightly curved. 5 This arc is concentric to the arc through which the lower end of the plumb bob (not shown) of the well survey instrument, swings and the purpose of this arcuate surface is to assure an accurate reading throughout all positions of the plumb bob. Obviously, when the disk 21 is positioned within the collar 24 on the arcuate upper surface 27, said disk will assume the same arc, as is clearly shown in Figure 5. Since the marking block 14 is to co-act with the disk 21, as will be hereinafter explained, the lower surface of 10 the block is also shown as being arcuate, the curvature of such lower surface being the same as the curvature of the supporting surface 27 and of the disk resting on said surface. It is 15 pointed out that the surface 27 could be flat, in which case the lower surface of the marking block would also be flat; however, as pointed out above, a more accurate reading is obtained by curving these surfaces concentric to the arc through which the lower end of the plumb bob 20 (not shown) swings.

The record element or disk 21 is a blank, that is, there are no markings on said disk. The disk is inserted within the collar 24 of the carrier so as to rest upon the supporting surface 27 of said carrier. After the disk is positioned, the marking device shown in Figures 1 to 3 is placed in position over the upper end of the carrier, as is clearly shown in Figure 5. The outer diameter 30 of the marking block 14 is the same as the bore 25 of the collar 24. Thus, when the skirt 11 is engaged over the upper end of the carrier, the marking block 14 enters the collar 24 and has a snug fit therein.

40 The marking block 14 is then moved downwardly until the projections 19 and 20 engage the upper surface of the disk or element 21. After this occurs, a downward pressure is exerted on the block and at the same time, said block is 45 rotated with respect to the disk 21 and carrier 22 by manually rotating the head or body 10 and block 14 secured thereto. Such rotation will result in the sharp edges of the projections 19 and 20 marking the upper surface of the disk 21. 50 It is preferable that the projections 19 and 20 be formed of a soft metal, such as brass or the like, whereby marking of the disk is facilitated. In some instances, it might be desirable to employ a paper disk provided with a suitable coating 55 on its upper surface, such coating further facilitating the marking thereof. It is pointed out that during the rotation of the block, the outer periphery of said block is engaging the wall of the collar 24 and is thereby held in positive axial alignment with the disk 21, whereby 60 lateral displacement of the block relative to the disk is prevented. In this manner, the proper positioning of the lines which are formed by the projections 19 and 20 is assured and said lines 65 are located in the proper concentric relation on the disk.

After the rotation of the block, the marking device is removed from the upper end of the carrier and a plurality of concentric lines 30 have 70 been formed on the disk. These lines are clearly shown in Figures 6 and 7 and have been identified by the numerals 30a, 30b, 30c, 30d and 30e, said lines having been formed by the projections 19a to 19e respectively. The center projection 75 20 on the marking block has formed a dot 20a.

at the center of the disk 21. Since, as explained, the concentric lines on the block 14 are properly positioned to indicate degrees from the center of the block, the lines 30a to 30e indicate degrees from the center of the disk 21. The positive guiding of the marking block during the marking operation assures that the lines will be properly positioned on the disk or element 21 and the chances for errors are eliminated. Of course, after the disk or element 21 has been marked it is inserted into a well survey instrument (not shown) and the record of the plumb bob position with relation to the disk is made. The provision of the lines on the disk 21 permit an accurate reading or interpretation of the indication made on the disk during operation of the well survey instrument.

The improved method is carried out entirely by hand. The blank disk is placed within its carrier or support and then the marking device shown in Figures 1 to 3 is engaged over the carrier to insert the block 14 within the collar 24 and in engagement with the disk therein. The marking device is then rotated to form the concentric lines in their proper position on the disk, after which the marking device is removed. The method permits the disk 21 to be cut out in blank and since the same marking device is used on all of the disks, all of the concentric lines formed thereon are in exactly the same position. There is no variance in the position of the lines on the disks and obviously, this is advantageous and substantially essential for accurate reading or interpretation of the complete well survey record.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A marking device for forming concentric lines on a record including, a body having a depending annular skirt, a circular marking block removably mounted within the skirt and having its outer wall spaced from the inner wall of the skirt to form an annular space therebetween, and a plurality of concentric projections on the lower surface of the block.

2. A marking device for forming concentric lines on a record disk including, a body having a depending annular skirt, a circular marking block removably mounted within the skirt and having its outer wall spaced from the inner wall of the skirt to form an annular space therebetween, and a plurality of concentric projections on the lower surface of the block, each projection having its lower edge sharpened to provide a knife-edge.

3. A marking device for forming lines on a record element including, a body having a depending annular skirt, a circular marking block disposed within the skirt and having its outer wall spaced from the inner wall of the skirt to

provide a space therebetween, and a plurality of marking projections on the lower surface of the block.

4. A marking apparatus for forming concentric lines on a record disk including, a support having a recessed upper end and adapted to receive the record disk, a marking block of substantially the same diameter as the recess of the support and movable therewith, whereby the outer surface of the block co-acts with the inner walls of the recess to axially guide said marking block as it moves therein, and a plurality of projections on the lower surface of the block and arranged to engage the upper surface of the record disk to effect marking of said disk.

5. A marking apparatus as set forth in claim 4, wherein the marking projections on the marking block extend from the block a distance which is less than the depth of the recess in the support, whereby said block enters the recess and is axially aligned therein prior to the engagement of the projections with the record disk.

6. A marking device for forming concentric lines on a record disk including, a body having a depending annular skirt, a circular marking block disposed within the skirt and having its outer wall spaced from the inner wall of the skirt to form an annular space therebetween, a plurality of concentric projections on the lower surface of the block, and a single tapered projection at the center of the block, all of said projections extending outwardly substantially equal distances from the surface of the block.

7. In combination, a support having its upper end recessed for receiving an element to be marked, a marking block of substantially the same diameter as the element and insertable within the recess of the support above the element within said recess, and marking projections on the bottom of said block adapted to engage the element within the support to mark the same.

8. In combination, a support having its upper end recessed for receiving a blank element to be marked, a marking block of substantially the same diameter as the recess in said support and insertable therein, and a plurality of concentric marking projections on the lower surface of the block and arranged to engage the upper surface of the element within the recess of said support and to mark said element when the block is rotated, the block co-acting with the support to guide said block and prevent lateral displacement thereof when said block is rotated.

9. A marking device as set forth in claim 1, wherein the lower surface of the block is convex and wherein all of said projections extend substantially the same distance from said convex surface.

10. A marking device as set forth in claim 4, wherein the lower surface of the marking block is slightly convex and wherein the wall of the recess which is adapted to receive the disk to be marked is arcuate and complementary to the convex lower surface of said block.

WILLARD J. OPOCENSKY.
